CLAIM

The ornamental design for a food warming tray, as shown and described.

DESCRIPTION

FIG. 1 is a front, top, right-side perspective view of a food warming tray, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a back, bottom and left-side perspective view thereof;

FIG. 9 is a first partially enlarged view thereof, taken from FIG. 1;

FIG. 10 is a second partially enlarged view thereof, taken from FIG. 1;

FIG. 11 is a third partially enlarged view thereof, taken from FIG. 1;

FIG. 12 is a fourth partially enlarged view thereof, taken from FIG. 1; and,

FIG. 13 is a partially enlarged view thereof, taken from FIG. 8.

The broken lines throughout the drawings depict portions of the food warming tray, that form no part of the claimed design.

The dot-dash broken lines of FIGS. 1 and 8-13 are included to show the partially enlarged views only and form no part of the claimed design.

1 Claim, 13 Drawing Sheets
